UNITED STATES PATENT OFFICE.

JAMES A. KEYES, OF NEW YORK, N. Y., ASSIGNOR TO N. S. PERKINS, OF NEW LONDON, CONNECTICUT.

COMPOSING-STICK.

SPECIFICATION forming part of Letters Patent No. 530,428, dated December 4, 1894.

Application filed May 11, 1894. Serial No. 510,854. (No model.)

To all whom it may concern:

Be it known that I, JAMES A. KEYES, a citizen of the United States, residing at New York city, in the county of New York and State of New York, have invented certain new and useful Improvements in Composing-Sticks, of which the following is a specification.

My invention relates to improvements in composing sticks, and the objects of my improvement are simplicity and economy in construction and efficiency in use.

In the accompanying drawings: Figure 1 is a plan view of my composing stick. Fig. 2 is an enlarged transverse section of the same on the line $\alpha\alpha$ of Fig. 1. Fig. 3 is a reverse plan view of the slide with one side in horizontal section and with one washer and screw removed in order to better show the eccentric, and Fig. 4 is a plan view on the same scale as Fig. 1, of the blank from which the slide is made.

My invention is in the nature of an improvement upon the invention patented to Albert M. White, January 7, 1890, and numbered 418,858, in which he employed a compressible slide in connection with means for forcing the same upon opposite edges of the stick. In said patent the slide was compressible by being composed of two parts which slid one upon the other. In my improvements, I make the ends of the slide yielding so that they may be compressed without any sliding movement, and whereby I am enabled to construct the slide of one piece of sheet metal.

The body of the stick A is or may be of any ordinary construction. I construct the slide B preferably from a single piece of sheet metal cut from the blank shown in Fig. 4 and bent into the form shown.

5 designates the top or body of the slide, from the inner edge of which the flange 6 is turned down to form the face of the slide against which the type is placed. At each end of the slide, and consequently upon opposite edges of the stick or body A, wings or flanges are turned down to form the front end 8 and rear end 7, the lower edge of each of said ends being turned under, as at 8^a Fig. 2, to take in under the body of the stick as shown. These ends being formed of sheet

metal are slightly flexible, thereby forming a compressible slide. A lug 9 is turned down from or formed upon the inside of the end 8, upon which to pivot the link 10 by means of the screw 11. On the inside of the top or body 55 5, I secure a fulcrum block 12 in any proper manner, as for example, by means of the screw 13, and upon this fulcrum block I pivot the operating lever 14, said lever being provided on its under side with an eccentric 15, 60 which eccentric is received by one end of the link 10. The link and lever may be held upon the fulcrum block 12 in any suitable manner, as for example, by means of the washer 16 and holding screw 17, which washer and screw are omitted from Fig. 3 in order to better illustrate the other parts.

The top or body of the stick 5 is formed from the middle portion 5 of the blank, Fig. 4, and the facing flange or side 6 is formed from the wing 6, while the front end is formed from the wing 8 and the rear end from the wing 7, the parts being bent up substantially on the broken lines 20, 21 and 18, while the flanges 8 are bent over substantially on the broken lines 19 of said Fig. 4. The lug 9 is cut out from the body of the wing 8, as at 9 in Fig. 4. The eccentric and link are so adjusted that when the lever handle 14 is turned into the position shown in the drawings, the yielding ends of the slide B are brought forcibly against the opposite edges of the stick A so as to hold the same firmly in the position set. By throwing the lever handle 14 backward, as indicated by broken lines in Fig. 1, 70 75 80 85 the eccentric is thrown into such a position as to release the ends 7 and 8 of the slide and permit them to swing outwardly sufficiently to slide along easily to any desired point upon the stick when they may be again fastened by returning the lever to its former position. It should be noted that the front end 8 of the slide B is so formed (see Fig. 2) as to press only on the bottom portion of the body or stick so as not to deflect the vertical flange 95 that extends along one edge thereof.

While I prefer to employ the eccentric and link for drawing the ends of the slide together, it is evident that my flexible slide may be used in connection with any ordinary 100

means for forcing its ends together. It is also evident that the ends could be forced together if only one of them was flexible. Furthermore my specific means for drawing the ends 5 of the slide together are not necessarily limited to the particular slide shown.

I claim as my invention—

1. The combination with the body of a composing stick, of a slide having a flexible end 10 and means for forcing its ends against the opposite side edges of the stick, substantially as described and for the purpose specified.
2. The combination with the body of a composing stick, of the sheet metal slide made in 15 one piece, and means for deflecting the end

pieces of said slide for binding them upon the opposite edges of the stick, substantially as described and for the purpose specified.

3. The combination of the body of the composing stick with the compressible slide B 20 having a fulcrum block, the operating lever having the eccentric 15, and a link 10 for connecting said eccentric and lever with two portions of said slide, substantially as described and for the purpose specified.

JAMES A. KEYES.
